UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

SWITCH MECHANISM.

Application filed June 2, 1919. Serial No. 301,264.

To all whom it may concern:

Be it known that I, REUBEN B. BENJAMIN, a citizen of the United States, residing at Chicago, in the county of Cook and State of Illinois, have invented new and useful Improvements in Switch Mechanisms, of which the following is a full, clear, concise, and exact description, reference being had to the accompanying drawing, forming a part of this specification.

My invention relates to switch mechanisms.

Among the objects of my invention are to provide a switch mechanism which will be simple in construction, efficient in operation and durable in use.

Further objects will appear from the detailed description to follow and from the appended claims.

In the drawings in which an embodiment of my invention is shown:

Fig. 1 is an axial section of an angle socket provided with a lever switch;

Fig. 2 is a section substantially on the line 2—2 of Fig. 1;

Fig. 3 is a plan view of the socket with the socket cap removed;

Fig. 4 is a section substantially on the line 4—4 of Fig. 1, looking up;

Fig. 5 is a section substantially on the same plane as that in Fig. 1 showing the switch mechanism in a different position than that in Fig. 1;

Fig. 6 is a bottom view of the upper portion of the insulating base;

Fig. 7 is a top view of the lower portion of the insulating base;

Fig. 8 is a section substantially on the line 8—8 of Fig. 3;

Fig. 9 is a perspective view of one of the spring contacts; and

Fig. 10 is a perspective view of the movable parts of the switch mechanism.

In order to give a general idea of the construction it is here stated that the embodiment shown comprises an angle socket having a casing for housing the receptacle contacts, binding terminals and switch mechanisms, which are mounted on a two

part insulating base, the casing having a removable cap or cover to permit access to the binding terminals for wiring and to facilitate the assembly and disassembly of the sockets.

Referring now to the drawings in detail, the key socket shown comprises the casing 12, the two-part insulating base 13, enclosed in the casing, the center and shell contacts 14 and 15 respectively, supported by the insulating base 13, and the switch mechanism 16 located substantially between the two parts of the insulating base 13, and supported thereby.

The casing 12 comprises the shell 17 surrounding the shell contact 15 and insulating base 13 and the cap 18 detachably secured to the shell 17, the removal of which cap permits access to the binding terminals 19, (Figs. 2 and 3) supported by the insulating base 13. An internally screw-threaded bushing 19^a is secured to the shell 17 in any suitable manner, by means of which the socket can be screwed on to a nipple, a set screw 20 being provided to prevent the bushing 19 from twisting on the nipple after it has been placed in the desired position. An insulating cup or disc 21 of fibre or other suitable material fits snugly in the cap 18 and prevents live parts, such as loose strands of the wires, from coming in contact with the metal parts of the casing. Also an insulating sleeve 22 of fibre or other suitable material is provided between the shell contact 15 and the metal shell 17. The metal shell 17 is cut out to provide a pair of oppositely disposed spring tongues 23 (Fig. 2) each provided with a lug 24 stuck up therefrom, for engaging within a channel formed by beading outwardly the lower edge of the cap 18 as indicated at 25. By pressing in on these spring tongues 23 the projections 24 are moved out of the channel in the bead 25 and the cap can be slipped off from the shell.

One of the binding terminals 19 is directly connected to the shell contact 15. The other binding terminal 19 is electrically connected to the center contact 14 through the switch mechanism 16, that is to say, the

binding terminal is connected to one contact or brush of the double break switch and the center contact is electrically connected to the other contact or brush of the double break switch. The electrical connection between the shell contact and its binding terminal 19 is by means of a screw 26 (Figs. 3 and 4) the head of which bears against a washer 27, which bears on an inwardly extending flange 28 of the shell contact, and the shank of which screw extends through an opening in said flange 28 and is threaded into the binding plate 29 of the binding terminal 19. The screw 26 not only serves as an electrical connection between the binding terminal 19 and the shell contact 15, but also assists in securing the shell contact in place on the insulating base 13, and in holding the upper and lower parts 30 and 31 of the insulating base together.

Before describing the electrical connection from the center contact to its binding terminal 19, I will first describe the switch mechanism which controls this circuit. This switch mechanism comprises two spring brushes or contacts 32 and 33 respectively, (Figs. 2 and 6) a movable switch arm 34 of conducting material, which snaps into and out of electrical engagement with the brushes 32 and 33, (thus making a double break in the circuit) a thumb lever 35 of insulating material for actuating the switch arm 34, and transmission mechanism 36 between the thumb lever 35 and the switch arm 34. The switch arm 34 and thumb lever 35 are both mounted on a common shaft or pin 37, which shaft is held in place by having its end located in notches or recesses 38 and 39 in the upper and lower sections 30 and 31 of the insulating base, (Figs. 6 and 7). The transmission mechanism 36 between the thumb lever 35 and the switch arm 34 comprises a link 40, (one end of which pivotally engages the thumb lever 35 and the other end of which has a swinging and sliding movement with respect to the switch arm 34,) and a coil compression spring 41 surrounding a portion of the link 36, one end of which coil spring bears on a shoulder 42 on said link 40 and the other end of which bears on a transversely extending portion 43 of the switch arm 34. One end of the link 36 extends to an opening 44 in the transversely extending portion 43 of the switch arm, the opening 44 being large enough to permit the link to slide and have a swinging movement with respect to the said transversely extending portion. The other end of the link 36 lies in a slot 45 of the thumb lever 35 (Figs. 5 and 10) and a short pin 46 is secured to this end of the link 36, the ends of the pin resting in notches in the end of the thumb lever 35 as indicated at 47.

Each of the spring contacts 32 and 33 comprises a base portion 48 (Figs. 2, 6 and

9) which bears on and is secured to the upper portion 30 of the insulating base, and an S-shaped spring contact portion 49 having a contact face 50 for engagement with the switch arm 34. The switch arm 34 and the contact brushes 32 and 33 may be sheet metal stampings, as may also the link 36. The thumb lever may be of sheet fiber or other suitable material cut to the proper shape. The brush 32 is electrically connected with one of the binding terminals 19 by means of a screw 51, which extends through an opening in the base 48 of the brush and is threaded into the binding plate 52 of the binding terminal 19 (Figs. 3 and 6). This screw 51 serves not only to make the electrical connection between the brush 32 and the binding plate 52 but also serves to hold the brush and binding terminal in place on the upper portion 30 of the insulating base. The other brush 33 is secured in place on the upper base portion 30 by means of an eyelet 53 (Figs. 6 and 8). This brush 33 is electrically connected with the center contact 14 by means of a screw 54 (Figs. 3 and 8) which extends through the eyelet 53 and is threaded into a washer 55 which bears against the base portion 56 of the center contact 14. The screw 54 thus serves not only as part of the electrical connection between the brush 33 and the center contact 14, but also serves to hold the center contact 14 in position on the lower portion 31 of the insulating base and helps to hold the portions 30 and 31 of the insulating base together. The switch mechanism 16 is located in a chamber 57 in the insulating base 13, this chamber being formed by opposed registering recesses in the upper and lower base sections 30 and 31. These registering recesses extend out to the edge of the insulating base portions 30 and 31 thus permitting the thumb lever 35 to extend outwardly so as to be accessible for operation from the outside of the casing, the casing being provided with a slot 58 in which the thumb lever 35 operates.

In addition to the screw 26 which helps to hold the shell contact in place on the insulating base, a screw 59 (Fig. 8) is provided which extends through registering openings in the base sections 30 and 31 and is threaded into a washer 60 which is seated against the flange portion 28 of the shell contact 15. This screw 59 thus not only serves to help to hold the shell contact 15 in place on the insulating base, but also helps to hold the base sections 30 and 31 together.

The device is wired by removing the cap 18, drawing in wires through the bushing 19 and securing them under the heads of the binding screws 61 of the binding terminals 19. The circuit (assuming that the switch is in closed position) is as follows: From the binding plate 52 through the screw 51,

brush 48, switch arm 34, brush 33, screw 54, center contact 14, through whatever translating device is inserted in the receptacle, to the shell contact 15, thence through the 5 screw 26 to the binding plate 29.

The switch is moved from the "on" position shown in Fig. 5 to the "off" position shown in Fig. 1 by pushing up on the thumb lever 35. The first part of the movement 10 of the thumb lever 35 causes no movement of the switch arm 34. However, when the pin 46 passes the dead center between the shaft 37 and the opening 44, the spring 41 begins to exert a pressure which will cause 15 the switch arm 34 to snap to a position shown in Fig. 1. In order to give a positive kick-off to the switch arm in case it sticks and is not released at the proper period of movement the lower base section 31 is provided with a projection 62 (Figs. 1 and 5) 20 located in position to be engaged by the link 36 in its movement. When this link 36 engages the projection 62 it positively forces the switch arm 34 free from the spring contacts 32 and 33 and the spring then causes the switch arm to snap away 25 from the spring contacts. As the switch arm 34 snaps away the circuit is quickly broken at two points, thus insuring a quick 30 double break action.

For moving the switch from the off position shown in Fig. 1 to the on position shown in Fig. 5, the thumb lever 35 is pressed downwardly, and when the pin 46 passes the dead center the switch arm 34 snaps to the "on" position. In order to insure positive actuation of the switch arm 34 in case it sticks the upper base section 30 is provided with a projection 63 (Figs. 1 35 and 5) located in position to be engaged by the link 36 in its movement. In case the switch arm 34 sticks the link 36 engages this projection 63 which gives it a positive kick-off, after which the spring 41 will snap 40 it quickly into the "on" position shown in Fig. 5.

In assembling the parts the switch mechanism may be first assembled as shown 50 in Fig. 10 and it is then secured in position in the recess 57 simply by placing the ends of the pin 37 in the notches 38 in the upper base section 30, and then placing the lower base section 31 in position with respect to the upper base section. The opposed 55 notches 38 and 39 thus serve to hold the entire assembled switch mechanism in its proper position.

Having thus described my invention, what I claim as new and desire to secure by 60 Letters Patent is:—

1. In a switch socket comprising a casing, a two-part insulating base in said casing, separable on a plane substantially transverse to the axis of said casing, a pair of 65 binding terminals supported on the upper

face of said upper base section, said base sections having a recess therebetween, a double-break switch mechanism located in said recess, comprising two brushes supported by said upper base, an electrical connection extending through said upper base section to one of said brushes, receptacle contacts supported by the lower base section, and electrical connections extending through the lower base section and electrically connecting the other of said brushes with one of said receptacle contacts, said switch mechanism comprising a snap switch arm for making and breaking contact with respect to both of said brushes simultaneously. 70 75 80

2. In a switch socket comprising a casing a two-part insulating base in said casing, separable on a plane substantially transverse to the axis of the casing, said base sections having a recess therebetween, binding terminals supported on the upper face of the upper base section, and a switch mechanism located in said recess comprising a switch arm pivoted to operate in a plane 85 substantially through the axis of said casing, and a pair of brushes both supported by the upper base section, and located on opposite sides of said switch arm, said switch arm operated to snap into and out of engagement with respect to both of said brushes simultaneously. 90 95

3. In a switch socket comprising a casing, a two-part insulating base in said casing, separable on a plane substantially transverse to the axis of said casing, said base sections having a recess therebetween, and a switch mechanism located in said recess, said switch mechanism comprising a snap switch arm pivoted to operate in a plane substantially through the axis of said casing, and yielding means for causing said switch arm to snap from one position to the other, one of said insulating bases being provided with means to give a positive start to said switch 100 105 110 arm.

4. In a switch socket comprising a casing, a two-part insulating base in said casing, separable on a plane substantially transverse to the axis of said casing, said base sections having a recess therebetween, a switch mechanism located in said recess, said switch mechanism comprising a pair of brushes, and a switch arm for making and breaking the connection between said 115 brushes, receptacle contacts supported by said lower base section, an eyelet extending through said upper base section for securing one of said brushes in place on said upper base section, and a screw extending through said eyelet for electrically connecting this brush with one of the receptacle contacts. 120 125

5. In a switch socket comprising a casing, a two-part insulating base in said casing, 130

separable on a plane substantially transverse to the axis of said casing, said base sections having a recess therebetween and a switch mechanism located in said recess, said switch mechanism comprising a pivoted switch arm, and a pair of brushes secured to said upper base section, each of said brushes

comprising the base portion bearing against the upper base section, and an S-shaped spring portion, one of the arms of which 10 engages said switch arm.

In witness whereof, I have hereunto subscribed my name.

REUBEN B. BENJAMIN.
